UNITED STATES PATENT OFFICE.

DARRELL WALLACE ISAACS, OF REDFERN, NEW SOUTH WALES, AUSTRALIA.

COLLAPSIBLE LUGGAGE CARRYING ATTACHMENT FOR USE WITH MOTOR AND OTHER VEHICLES.

Application filed December 28, 1923, Serial No. 683,248, and in Australia May 22, 1923.

Other devices have been invented for the purpose of enabling luggage to be carried upon the running boards of motor cars, but some of these are expensive to manufacture while others require a certain amount of manipulation before they are adjusted in the carrying position.

The object of this invention is to provide a simple and efficient means for carrying the luggage, as stated above, such means being capable of being instantly placed in position for use or collapsed along the edge of the running board in such a manner that it forms no obstruction when a person is entering or alighting from the vehicle.

The invention consists of a parallel motion metal frame or fence having two horizontal members pivoted to any suitable number of vertical members. The horizontal members will be pivoted upon opposite sides of the vertical members, a washer or distance piece being placed between one of the horizontal members and each vertical member to which it is pivoted so as to form a space in which a part of the bracket will lie when the frame or fence is collapsed. The vertical members will be spaced so that the distance between them will be greater than the distance between their lowest pivotal point and their outer extremities.

The lower end of each vertical member is pivoted to an upturned portion of a bracket that is suitably secured to the underside of and which projects beyond the outer edge of the running board. The projecting horizontal portion of the bracket is provided with a transverse slot in which the lower extremity of the vertical member will lie when the appliance is in use.

A spring catch will be provided and is so arranged that as the frame or fence is raised to its operative position it will co-operate with the slots in the bracket and automatically lock the frame in position. This catch may be released when the frame is to be collapsed.

The appliance while primarily devised for use on the running boards of motor cars is also applicable to the sides of motor and other lorries in order to provide side walls which may be collapsed when it is desired to use simply the flat top of the wagon.

In order that the invention may be thoroughly understood, a more detailed description will now be given and reference will be

made to the accompanying sheet of drawings in which:—

Fig. 1 is a perspective view of the appliance secured to the running board of a motor car.

Fig. 2 is an underneath perspective view of the appliance in its collapsed position.

Fig. 3 is an underneath perspective view of the locking bracket showing the spring catch in engagement with the vertical member of the metal fence.

Fig. 4 is a similar view to Fig. 3, but with portion of the locking bracket and spring catch cut away to economize space, the view showing the spring catch depressed so as to disengage it from the lower end of the vertical member and enable the frame or fence to be collapsed.

The appliance is provided with metal brackets 10 by means of which it is secured to the running board 11 of a motor car by screws that pass through the countersunk holes 12.

The brackets consist of a metal plate of a suitable thickness, one edge 13 being turned upwardly for the purpose of forming a dwarf wall to which the vertical members 14 of the frame are pivoted. In securing the brackets 10 to the running board 11 a space will be left between the edge of the running board and the inner face of the dwarf wall of the brackets in order to accommodate part of the frame when it is in its collapsed position.

Each bracket 10 is slotted as at 15 so that when the frame is opened out as shown at Fig. 1, one side of the vertical member 14 will abut against one end of the slot and thereby prevent the frame from being moved any further in that direction, while the flat face of the vertical member opposite to that side which

contacts with the dwarf wall will form a rubbing contact with a longitudinal edge of the slot and thereby assist in preventing side movement of the vertical member. The frame consists of horizontal members 16-16^a and vertical members 14 pivoted together on the

parallel motion principle, but in order to enable it to occupy the minimum space when it is closed down or collapsed, the horizontal members are pivoted at 17 upon opposite sides of the vertical members 14 thus allowing the horizontal members to lie in the same horizontal plane. Between each of the vertical members 14 and the horizontal member

16^a is a distance piece 18 that forms a longitudinal space 18^a in which the dwarf wall 13

106

110

will lie when the frame is collapsed, the horizontal member 16^a lying outside the dwarf walls. The distance between the pivotal points 19 on the dwarf wall will be such as to enable each vertical member 14 to lie parallel with one another and in the same plane. The underside of one of the brackets 10 is provided with a spring catch 20, one end of which is rigidly secured thereto by the rivet 21, the other end projecting over the slot 15 and being secured, so as to prevent lateral movement by the U shaped metal strap 22 riveted to the bracket. The lower end of the vertical member that is pivoted to the locking bracket is rounded as at 23 and this rounded section engages and depresses the spring catch as the frame is being raised to its operative position, a section being cut out of the end of the vertical member 14 to form a recess 24 into which the catch 20 will spring as the member 14 reaches the vertical portion, thereby locking the member 14 between the side of the catch and the end of the slot 15 and preventing movement in either direction. It will be seen that by locking one of the vertical members the whole frame is locked and cannot be again moved until the spring is disengaged by hand from engagement with the recess 24. If desired each bracket may be provided with a slot 25 through which a suitable strap may be passed and thence around the luggage and securely fastened in any suitable manner as an additional safeguard against the movement of the luggage packed upon the running board.

I claim:

1. A collapsible luggage carrying device particularly adapted for use on the running boards of motor cars, comprising a plurality of brackets rigidly secured to the under surface of the running board and projecting laterally therefrom and each terminating in a connecting portion, a plurality of vertical members having the lower ends pivoted to the connecting portions of the brackets, a pair of horizontal members arranged on opposite sides of the vertical members, one of the horizontal members being pivoted directly to each of the vertical members and the other of the horizontal members being pivoted in spaced relation to the other sides of the vertical members so as to permit the horizontal and vertical members being collapsed to lie on the brackets between the connecting portions thereof and edge of the running board and flush with the upper surface of the running board, and means for locking the device in its fully extended position.

2. A collapsible luggage carrying device particularly adapted for use on the running boards of motor vehicles, comprising a plurality of brackets secured to the under surface of the running board, a plurality of vertical members having the lower ends pivoted to the brackets, two horizontal members piv-

oted upon opposite sides of the vertical members, each bracket including a metal plate one side of which is turned upwardly to form a shallow vertical wall to which the corresponding vertical member is attached, the plate being formed with a slot positioned at the angle formed by the upturned wall, the slot being positioned and dimensioned so as to enable the lower end of the vertical member to move thereinto and to make a sliding contact with the longitudinal edge thereof when it is being raised from horizontal to the vertical position and to prevent it from being moved beyond such vertical position.

3. A collapsible luggage carrying device particularly adapted for use on the running boards of motor cars, comprising a plurality of brackets secured to the running board, a plurality of vertical members the lower ends of each of which are pivoted to the brackets, two horizontal members pivoted upon the side of the vertical member, each of the brackets being provided with slots through which the lower portion of the corresponding vertical member projects, a tooth formed on the lower extremity of each vertical member, a plate spring having one end secured to the underside of the bracket and the other end extending over the slot in the bracket and depressed by the tooth when the vertical member is swung to a raised position and engageable beyond the tooth so as to lock each vertical member when the latter has been raised to the full extent so as to prevent collapsing, substantially as and for the purposes set forth.

4. A collapsible luggage carrying device particularly adapted for use on the running boards of motor vehicles, comprising a plurality of brackets having the lower main portions secured to the under surface of the running board and formed with relatively short upright walls with the forward extremities positioned in spaced relation to the adjacent outer edge of the running board, vertical members having the lower ends secured to the upright portions of the brackets, horizontal members positioned upon opposite sides and pivoted to the vertical members, distance pieces interposed between each vertical member and the outer horizontal member so that when the members are collapsed the vertical members and the inner horizontal member will lie within the space between the upright portions of the brackets and the forward edge of the running board while the outer horizontal member will be arranged on the outside of the upright portions of the brackets so that the luggage carrying device when collapsed will not interfere with the persons stepping on the running board, substantially as and for the purposes set forth.

In testimony whereof I hereunto affix my signature.

DARRELL WALLACE ISAACS.
